BOX

Maurice Henry Robin, Cheadle, England

Application May 24, 1947, Serial No. 750,323
In Great Britain December 18, 1946

8 Claims. (Cl. 220—41)

1

This invention relates to boxes of the kind fitted with a roll-type lid or closure; that is to say, a lid capable of being slidden along suitable tracks from a closure position to an inoperative and preferably concealed position affording free access to the box. Such roll-type lids are usually formed of a plurality of slats extending between the tracks and connected together so as to provide an assembly which is longitudinally flexible whilst having adequate stiffness in a direction 10 normal to such slats.

Boxes of the kind aforesaid are made for a variety of uses, for example as pencil boxes, and by the present methods of manufacture the tracks for the edges of the lid or closure are formed as grooves in the sides of the box. Such boxes were originally made of wood as an assembly of sides, ends and a false bottom or back, and the forming of the grooves in the side was quite a simple operation. With recent developments of mouldable materials, known generally as plastics, many articles are now made by moulding, one of the major advantages of which is that an article such as an ordinary box, i. e. one not having a roll-type lid, can be made of a smaller number of parts, thus reducing or eliminating assembly operations and combining lightness with strength. The manufacture of a moulded box with a roll-type lid presents a considerable problem as regards the formation of the tracks for the lid, the only known alternative methods of forming such tracks being either to make the sides as separate parts, when simple moulds can be used, or by using a relatively complicated or expensive mould.

The object of the present invention is to provide a simple and improved manner of manufacture by moulding of a box of the kind fitted with a roll type of lid or closure.

Referring to the drawings:

Fig. 1 is an exploded perspective view showing the components of a pencil box body made in accordance with the present invention;

Fig. 2 is a plan view of the assembled box, with the roll-type lid fitted but partly retracted to show the interior of the box body;

Figs. 3 and 4 are sections on the lines 3—3 and 4—4, respectively, of Fig. 2;

Fig. 5 is a section on the line 5—5 of Fig. 3.

In the construction illustrated, the body of the box comprises an outer shell A which is open at the bottom, a lining or core or inner shell B, and a base member C, each of these components being formed as a one-piece moulding.

The outer shell A is rectangular in plan view and has an elongated aperture D in its top wall a' whose junctions with the end walls a² are radiused as at E.

The side walls a³ of the shell A are flat and each is rebated internally to provide, below and

2

parallel to the top wall a', a downwardly facing shoulder F which extends the full length of the wall a' and has one end curved downwardly in a 90 degree arc, as at G, substantially concentrically with the adjacent radiused portion E of the shell.

A further rebate H in the lower portion of each side wall a³ provides adjacent and parallel to the free edge of the latter, a second downwardly facing shoulder.

The lining B aforesaid is constructed as an open-topped rectangular box with a central longitudinal wall I dividing its interior into two compartments, one of which is of full length as at J, whilst the other is subdivided by transverse walls K, L into three sections M, N, O of progressively diminishing size.

In assembling the box body, the lining B is inserted upwardly into the shell A until the edges 20 of its side walls b' abut the shoulders F, the length and width of the lining being such that it fits snugly between the end walls a² and rebated side walls a³ of the shell.

Under these conditions the end walls b² of the 25 lining B are disposed beneath the ends of the shell aperture D and each end wall b² carries longitudinally extending vertical webs which abut the cover end walls a² to position the lining.

At the end of the lining adjacent the compartment O thereof two of the webs aforesaid may be formed as substantially triangular extensions P of the side walls b', and at the other end of the lining there may be three semi-circular webs Q which form continuations of the side walls b' and central partitions I respectively, the edges 35 of the outer webs Q fitting against the arcuate shoulders G of the shell A.

The base member C is shaped and dimensioned so as to fit snugly into the lower rebates H of the shell side walls a³ and between its end walls a², an upstanding lip R along both sides and across one end of the base member C abutting the underside of the lining B to hold the latter in place.

At the end of the base member adjacent the webs Q, is formed an upstanding wall S which engages the adjacent end wall a² of the shell and whose upper corners are connected to the longitudinal parts of the lip R by integral gussets T having their edges shaped to fit against the webs Q.

The upper face of the base member C is recessed so as to leave a ledge U extending along each side thereof adjacent the lip R, these ledges having arcuate continuations V on the inner faces of the gussets T as clearly shown in Fig. 1.

It will be appreciated that when the components A, B, C are assembled together, there 60 are formed, along opposite sides of the box body

thus produced, channels shaped like recumbent letter U.

The upper run of each channel is bounded by the underside of the shell top 'a' and the top of the lining side wall 'b', which is wider than the shoulder F, the base of the channel being formed by the inner face of the shell side wall 'a³' (see Fig. 4). Similarly the lower run of each channel is defined by the bottom of the lining B and the adjacent ledge U of the base member C, in conjunction with the inner face of the lip R.

As shown in Figs. 3 and 5, the semicircular bend of each channel, bounded internally by the edge of the adjacent web Q, is defined at its outer periphery by the curved ledge V on the base member, and a corresponding ledge W formed inside the shell A concentrically with the shoulder G. The base of this section of each channel is formed by the inner faces of the shell side 'a³' and the base member gusset J.

The U-shaped channels aforesaid form tracks for slidably receiving the lateral edges of a roll-type lid X which latter is placed in the lower runs of the channels, between the lining B and base member C, before these components are secured within the outer shell A.

The roll-type lid X, which may be constructed in any suitable manner (but preferably as described in my co-pending application Serial No. 687,581 filed August 1, 1946) is made of such a length as to cover the shell aperture D, or to leave substantially the full length of the lining compartments exposed, according to whether such lid is disposed in the upper or lower runs of its guiding tracks.

In use, the compartment J of a pencil box so constructed may accommodate long pencils, whilst penholders may be placed in the shorter compartment M. The compartments N, O may serve for the reception of small articles, but it is preferred to leave the smallest compartment O empty and to accommodate articles such as pen-nibs in the compartment N beneath a subsidiary lid Y which covers the compartments N, O.

The lid Y, which lies beneath the aperture D and normally fits flush with the upper edges of the lining walls 'b', is capable of being rocked upon the partition wall L by the application of pressure to the part thereof above the compartment O, so that the other part of the lid is raised to expose the contents of the compartment N.

Preferably such other part of the lid Y is shaped as a trough Z whose underside normally projects into the compartment N and which may be used to accommodate an article such as an eraser.

The lid Y is, of course, positively retained in position whilst the roll-type lid is closed and provides an effective safeguard against the free movement of the lid X being obstructed by small articles from the compartments N, O.

What I claim is:

1. A box comprising an outer unitary shell open at top and bottom, an inner shell fitted into said outer shell and constituting a container open at the top, a roll-top lid, a base fitted into the bottom of said outer shell, said inner shell being spaced from the top of said outer shell and from said base to provide upper and lower tracks, said lid operating in said tracks, integral longitudinal shoulders along the sides and extending below the under face of said outer shell, the upper longitudinal edges of said inner shell being in contact with said shoulders to provide a pair of track spaces with said outer shell, the side walls of said inner shell being in substantial contact with the side walls of said outer shell, integral longitudinal ledges along the sides of the upper face of said base, upstanding lips along said sides of said base extending above said ledges, the lower longitudinal edges of said inner shell being in contact with said lips to provide a pair of track spaces with said base between said ledges and said inner shell, one end of said outer shell shoulders merging with the corresponding end of said base ledges to form a pair of continuous tracks.

2. A box comprising an outer unitary shell open at top and bottom, an inner shell fitted into said outer shell and constituting a container open at the top, a roll-top lid, a base fitted into the bottom of said outer shell, said inner shell being spaced from the top of said outer shell and from said base to provide upper and lower tracks, said lid operating in said tracks, integral longitudinal shoulders along the sides and extending below the under face of said outer shell, the upper longitudinal edges of said inner shell being in contact with said shoulders to provide a pair of track spaces with said outer shell, the side walls of said inner shell being in substantial contact with the side walls of said outer shell, integral longitudinal ledges along the sides of the upper face of said base, upstanding lips along said sides of said base extending above said ledges, the lower longitudinal edges of said inner shell being in contact with said lips to provide a pair of track spaces with said base between said ledges and said inner shell, one end of said outer shell shoulders merging with the corresponding end of said base ledges to form a pair of continuous tracks.

3. A box comprising an outer unitary shell open at top and bottom, an inner shell fitted into said outer shell and constituting a container open at the top, a roll-top lid, a base fitted into the bottom of said outer shell, said inner shell being spaced from the top of said outer shell and from said base to provide upper and lower tracks, said lid operating in said tracks, integral longitudinal shoulders along the sides and extending below the under face of said outer shell, the upper longitudinal edges of said inner shell being in contact with said shoulders to provide a pair of track spaces with said outer shell, the side walls of said inner shell being in substantial contact with the side walls of said outer shell, integral longitudinal ledges along the sides of the upper face of said base, upstanding lips along said sides of said base extending above said ledges, the lower longitudinal edges of said inner shell being in contact with said lips to provide a pair of track spaces with said base between said ledges and said inner shell, one end of said outer shell shoulders merging with the corresponding end of said base ledges to form a pair of continuous tracks.

4. A box comprising an outer unitary shell open at top and bottom, an inner shell fitted into said outer shell and constituting a container open at the top, a roll-top lid, a base fitted into the bottom of said outer shell, said inner shell being spaced from the top of said outer shell and from said base to provide upper and lower tracks, said lid operating in said tracks, integral longitudinal shoulders along the sides and extending below the under face of said outer shell, the upper longitudinal edges of said inner shell being in contact with said shoulders to provide a pair of track spaces with said outer shell, the side walls of said inner shell being in substantial contact with the side walls of said outer shell, integral

5. A box comprising an outer unitary shell open at top and bottom, an inner shell fitted into said outer shell and constituting a container open at the top, a roll-top lid, a base fitted into the bottom of said outer shell, said inner shell being spaced from the top of said outer shell and from said base to provide upper and lower tracks, said lid operating in said tracks, integral longitudinal shoulders along the sides and extending below the under face of said outer shell, the upper longitudinal edges of said inner shell being in contact with said shoulders to provide a pair of track spaces with said outer shell, the side walls of said inner shell being in substantial contact with the side walls of said outer shell, integral

longitudinal ledges along the sides of the upper face of said base, upstanding lips along said sides of said base extending above said ledges, the lower longitudinal edges of said inner shell being in contact with said lips to provide a pair of track spaces with said base between said ledges and said inner shell, one end of said outer shell shoulders merging with the corresponding end of said base ledges to form a pair of continuous tracks, and a flange around the top of said outer shell to retain said lid in position within said box.

5. A box comprising an outer unitary shell open at top and bottom, an inner shell fitted into said outer shell and constituting a container open at the top, a roll-top lid, a base fitted into the bottom of said outer shell, said inner shell being spaced from the top of said outer shell and from said base to provide upper and lower tracks, said lid operating in said tracks, integral longitudinal shoulders along the sides and extending below the under face of said outer shell, the upper longitudinal edges of said inner shell being in contact with said shoulders to provide a pair of track spaces with said outer shell, the side walls of said inner shell being in substantial contact with the side walls of said outer shell, integral longitudinal ledges along the sides of the upper face of said base, upstanding lips along said sides of said base extending above said ledges, the lower longitudinal edges of said inner shell being in contact with said lips to provide a pair of track spaces with said base between said ledges and said inner shell, one end of said outer shell shoulders merging with the corresponding end of said base ledges to form a pair of continuous tracks, complementary curves at one end of said inner and outer shells and base to provide a track joining said upper and lower tracks.

6. A box comprising an outer unitary shell open at top and bottom, an inner shell fitted into said outer shell and constituting a container open at the top, a roll-top lid, a base fitted into the bottom of said outer shell, said inner shell being spaced from the top of said outer shell and from said base to provide upper and lower tracks, said lid operating in said tracks, integral longitudinal shoulders along the sides and extending below the under face of said outer shell, the upper longitudinal edges of said inner shell being in contact with said shoulders to provide a pair of track spaces with said outer shell, the side walls of said inner shell being in substantial contact with the side walls of said outer shell, integral longitudinal ledges along the sides of the upper face of said base, upstanding lips along said sides of said base extending above said ledges, the lower longitudinal edges of said inner shell being in contact with said lips to provide a pair of track spaces with said base between said ledges and said inner shell, one end of said outer shell shoulders merging with the corresponding end of said base ledges to form a pair of continuous tracks.

7. A box comprising an outer unitary shell open at top and bottom, an inner shell fitted into said outer shell and constituting a container open at the top, a roll-top lid, a base fitted into the bottom of said outer shell, said inner shell being spaced from the top of said outer shell and from said base to provide upper and lower tracks, said lid operating in said tracks, integral longitudinal shoulders along the sides and extending below the under face of said outer shell, the upper longitudinal edges of said inner shell being in contact with said shoulders to provide a pair of track spaces with said outer shell, the

side walls of said inner shell being in substantial contact with the side walls of said outer shell, integral longitudinal ledges along the sides of the upper face of said base, upstanding lips along said sides of said base extending above said ledges, the lower longitudinal edges of said inner shell being in contact with said lips to provide a pair of track spaces with said base between said ledges and said inner shell, one end of said outer shell shoulders merging with the corresponding end of said base ledges to form a pair of continuous tracks, a compartment in said box having a vertical wall, a subsidiary lid for said compartment extending over said partition and adapted to be opened by pressure on the extension thereof, said subsidiary lid being adjacent to said first lid when the latter is closed and constituting means for preventing accidental opening of said subsidiary lid.

8. A box comprising an outer unitary shell open at top and bottom, an inner shell fitted into said outer shell and constituting a container open at the top, a roll-top lid, a base fitted into the bottom of said outer shell, said inner shell being spaced from the top of said outer shell and from said base to provide upper and lower tracks, said lid operating in said tracks, integral longitudinal shoulders along the sides and extending below the under face of said outer shell, the upper longitudinal edges of said inner shell being in contact with said shoulders to provide a pair of track spaces with said outer shell, the side walls of said inner shell being in substantial contact with the side walls of said outer shell, integral longitudinal ledges along the sides of the upper face of said base, upstanding lips along said sides of said base extending above said ledges, the lower longitudinal edges of said inner shell being in contact with said lips to provide a pair of track spaces with said base between said ledges and said inner shell, one end of said outer shell shoulders merging with the corresponding end of said base ledges to form a pair of continuous tracks, a compartment in said box having a vertical wall, a subsidiary lid for said compartment extending over said partition and adapted to be opened by pressure on the extension thereof, said subsidiary lid being adjacent to said first lid when the latter is closed and constituting means for preventing accidental opening of said subsidiary lid, said auxiliary lid having a depressed portion over said compartment to hold an article therein.
